UNITED STATES PATENT OFFICE.

HUGH GORDON MACWILLIAM, OF NEW ROCHELLE, NEW YORK.

WINDOW.

Application filed May 18, 1920. Serial No. 382,434.

To all whom it may concern:

Be it known that I, HUGH G. MACWILLIAM, a subject of the King of Great Britain, and resident of New Rochelle, in the county of Westchester and State of New York, have invented certain new and useful Improvements in Windows, of which the following is a specification.

My invention relates to windows and has particular reference to a type which combines the advantages of a sliding sash for general purposes and a swinging member on each sash acting as a frame for the glass and by the use of which swinging feature the glass may be easily and readily cleaned both on the inside and the outside faces.

One of the objects of my invention is to provide window sashes of the type described which are practical and of low cost and which can be easily placed in any ordinary window frame and in such a manner that repairs may be easily made and outside screens, storm sashes, or blinds of full or half length may be permanently attached without interfering with the operation of the window.

A further object is to produce an efficient combination of sashes which may each have a maximum of light giving space.

Another object is to provide means for making all joints around the swinging members water and air tight as nearly as may be required.

Further objects are to provide proper joints between the sliding sashes when closed, to eliminate any rough projection on either surface of the sashes, and to provide locking means for said swinging members, locking means for said sliding sashes when closed, and aligning means for said sliding sashes when in registering position whereby the upper swinging member may be swung through the lower sash when the lower swinging member is open, and without danger of window breakage.

Another object is to provide supporting hinged means whereby the lower swinging member may swing clear of the upper swinging member when the latter is opened. Other objects will become apparent as the description proceeds.

My invention consists in such novel features of construction and arrangement of parts as are hereinafter described and particularly pointed out in the claims hereto appended, one practical embodiment of my

invention being shown in the accompanying drawing in which—

Fig. 1 shows the general appearance of a window having my improved features. 60

Fig. 2 shows a part vertical side section through the window sashes, with the sashes and swinging members closed and locked.

Fig. 3 shows a similar part section with both sashes aligned in registering position. 65

Fig. 4 is a detail view in section on line 4—4 of Fig. 3 showing wide opening of the upper swinging member.

Fig. 5 is a detail of the sash construction.

Fig. 6 is a detail of the flush swinging 70 member locking means.

Fig. 7 is a top view of the sashes showing the beveled feature of the side edges of the swinging members.

Similar reference characters refer to similar parts throughout the several views. 75

I intend no limitations other than those of the claims—

A window frame 1 of ordinary type is illustrated having fitted thereto my improved 80 sashes, top 2 and bottom 3 both of which slide in a well known manner, the weight cords of the sashes being shown for example as at 4 passing over pulleys 5, only one of which is shown. These sashes 2, 3, may 85 have each an outside, sliding, rigid frame and an inner swinging member 9, 10, respectively; the swinging member 9 of the upper sash being smaller than the smallest part of the opening provided in the lower 90 sash for closure by swinging member 10.

Locking means are provided as for example a lock 6 on the lower sash frame 3 and a catch 7 on the lower rail of swinging member 9. A similar catch 7' may be 95 placed on the upper portion of the sash 2 arranged to take into a recess 8 in the window casing 1 when the upper sash is closed. By sliding sash 2 down and sash 3 up in the usual manner the two sashes may be 100 brought into registering position (Fig. 3) in which position the catch 7' of the upper sash may coact with the lock 6 of the lower sash to hold the two window sashes fixedly together. The swinging members 9, 10, 105 may then be swung inwardly one after the other as for cleaning or mending purposes.

The swinging members are locked in closed position as by flush locks 11 (Fig. 1 and Fig. 6). These locks may be opened 110 by the insertion of a key and may be of any standard type but if used should be flush

with the frame of the sash to permit sliding and prevent catching of blowing curtains and the like.

When the sashes are in registering position (Fig. 3) the lower sash is inside. The swinging member 10 is opened first and swings clear into the room by reason of hinges 12 which are sunk into the sash frame flush with the beveled edge 13 against 10 which the beveled edge 14 of the swinging frame abuts, the other part of the hinge being flush therein. Sashes 2 and 3 are provided with weatherstrip frames 15, 15' respectively, having each a periphery of the 15 shape and bevel of the sides of the respective swinging member opening and having an angle cross section as shown. The frames 15, 15' are disposed between the members 3 and 10 and 2 and 9 respectively when the 20 swinging members are in normal position, and each frame provides a lip portion against which the respective swinging member tightly closes. One flange of each weatherstrip frame is sunk into the beveled 25 edges 13 of the rails of its sash (Fig. 4), and a channel or groove is cut in the face of each of the swinging members 9, 10, as shown at 16, 16' (Fig. 4) which interfits with the upturned lip portion of the 30 weather strip 15, 15', when the swinging members are closed.

The upper swinging member 9 is supported by a hinge 19 (Fig. 4) sunk in both the sash and the member edges and the member 25 9 may be opened at least 90 degrees through the lower sash opening when the member 10 is swung fully open.

In closed position of the sashes the swinging member 9 cannot be opened because it 40 abuts the lower sliding sash 3 and in fact

the member 9 can only be opened with both sashes registering.

With both sashes closed the lower sash cross bar interlocks at the center joint 21 with the upper sash cross bar (Fig. 2). In 45 order to provide for this joint and yet permit sliding the sashes together the lower sash top cross bar is wider than the bottom cross bar while the upper sash top cross bar is narrower than its bottom cross bar as 50 shown.

Having thus described one embodiment of my invention what I desire to claim is:—

1. In a window, an upper sliding sash frame having a centrally disposed swinging member and a lower sliding sash frame having a centrally disposed swinging member, means to lock both sashes together in registering position at any point and means whereby said upper sash swinging member 55 may be swung inwardly through a centrally disposed opening in said lower sash frame, when the swinging member of said lower sash frame is open.

2. In a window, an upper sliding sash 65 frame having a centrally disposed swinging member and a lower sliding sash frame, having a centrally disposed swinging member, means to lock said frames together in closed position, additional means adapted 70 to coact with part of the first mentioned means to lock said frames together in registering position, and locking means for said swinging members, substantially as described.

Signed at New Rochelle, in the county of Westchester and State of New York, this 75 18th day of March A. D. 1920.

HUGH GORDON MACWILLIAM.
